PAPER-CARTON OPENER

Lewis Walter Goldstein, Pittsfield, Mass.

Application November 11, 1932
Serial No. 642,214

26 Claims. (Cl. 164—83)

The present invention relates to cutting instruments and more particularly to instruments for opening corrugated paper boxes or cartons used for packing purposes.

It has heretofore been proposed to open cartons of the above-described character by cutting through and along the side walls of the carton, just below the top thereof, thereby permitting easy removal of the top and exposure of the contents. One convenient proposal embodying this idea has involved mounting a razor blade fixedly upon a carriage that is manipulated longitudinally along the carton, with the blade cutting into the side walls in order to produce the said cutting operation therein. Prior proposals of this nature, however, have been of such a character that the instruments have not been adapted for use with different types of boxes or cartons, with the result that sometimes, for some cartons, the cutting has been either too high or too low along the sides of the box. If the blade is fixed too high on the instrument, it may not cut low enough down upon a box of thicker corrugated paper, with the result that an imperfect severing operation may be produced; and if the blade cuts too low below the top, it may result in damaging the goods contained within the carton. If the goods are of such nature as expensive women's clothing, for example, the damage may be irreparable. The construction, furthermore, has been such that manipulation of the instrument has been awkward and more or less difficult, and the instrument has not fitted the cartons properly. Prior proposals have been subject to other defects also.

An object of the present invention accordingly is to provide a new and improved instrument of the above-described character with the use of which it shall be possible to effect a cut in just the right position on any box, thereby insuring a proper cut and, at the same time, one that shall not involve damaging the contents.

Another object is to provide the instrument with a suitably operating blade that may be adjusted to the particular box under consideration.

A further object is to provide an instrument, the body of which, handle included, is of one piece.

A further object is to provide an instrument of the above-described character that shall be adapted for more facile manipulation.

A further object is to provide an instrument of this character that shall be cheaper to manufacture and efficient in operation.

A further object is to shape the instrument so that it shall fit better the boxes that it is adapted to open. Preferably, the instrument is provided with dihedral faces for fitting corresponding faces of the box, the dihedral faces being disposed at an angle somewhat more than a right angle, and provided with a groove along the intersection or junction of the faces to receive rounded or bunched edges of the boxes.

Other and further objects will be explained hereinafter in connection with the accompanying drawing, in which Fig. 1 is a perspective of a carton box showing a preferred embodiment of the present invention thereon; Fig. 2 is a perspective upon a larger scale of the instrument shown in Fig. 1, but looking from the opposite direction; Fig. 3 is a perspective of an upper clamping member; Fig. 4 is a perspective of a preferred blade; Fig. 5 is a perspective of a preferred lower clamping member; Fig. 6 is a side elevation of the instrument shown in Figs. 1 and 2; Fig. 7 is an underside plan of the same; Fig. 8 is an end elevation; and Fig. 9 is a corresponding end elevation of a modification.

According to the preferred embodiment of the invention, the instrument is constituted of a dihedral angle member and a handle, all in one piece, preferably made, as by casting or molding, of some suitable metal, such as aluminum. The faces of the dihedral angle are indicated at 2 and 4, and the handle at 6. The handle 6 extends from the face 2 longitudinally of the instrument, but rather close to the line 8 of intersection of the faces 2 and 4. The instrument is provided with a cutting blade 10 which is adapted to extend into a side wall 12 of a corrugated-paper or other carton, as illustrated more particularly in Fig. 1, so that, as the instrument is moved forward in the direction of the arrow of Fig. 1, the blade will produce a cut parallel to the top 14 of the instrument, as indicated at 14. The blade is positioned very near to the line of junction of the faces 2 and 4, which faces are of so relatively great magnitude that the blade is, in effect, positioned a considerable distance away from all the edges of the instrument, thus hiding the blade when the likelihood of accidental contact therewith is minimized. This is an important safety feature, preventing accidental injury of the operator.

The instrument is moved in the above-described manner along the four sides of the top 16 of the carton to produce a cut 14 in each side wall, just below the top 16, thereby severing the top 16 from the carton. The faces 2 and 4 are adapted

60

65

70

75

100

105

110

to engage, respectively, the top 16 and the side walls, such as the side wall 12, of the carton. In order that the edges 18 between the top 16 and the side walls of the carton may be properly received in the junction between the faces 2 and 4, particularly when these edges 18 are bunched or rounded over, the face 4 is provided with a groove 20 at the junction between the faces 2 and 4. This groove 20 plays a further function 5 for receiving the projections 50 on the edges 18, as will presently be described.

The angle between the top 16 and the side walls of the carton is usually somewhat more than a right angle, because, being made of paper, the 10 side walls and the top 16 are sometimes forced to bulge in the neighborhood of the edges, like the edges 18. It is therefore preferred to have the angle between the faces 2 and 4 also somewhat more than a right angle. That is, the 15 thickness of one or both faces 2 and 4 is less at the extremities 56 than near the junction line between the faces 2 and 4. The end or ends 56 may, for example, be $\frac{1}{8}$ inch less thick than 20 near the said junction line. This is shown exaggerated, for clearness, in the drawing.

For some kinds and thicknesses of paper, the blade 10, if permanently situated, might cut into the side wall 12 at a distance so slightly below the top 16 as possibly not to sever the complete top 25 16 from the carton. On the other hand, if the blade 10 is positioned lower below the top 16 so as to accommodate boxes of this type, then for boxes of other types the blade 10 may be positioned so low down below the top 16 as to engage 30 the goods inside the box. If the goods are fragile clothing or of similar nature, for example, this 35 may result in damaging the contents.

In accordance with the present invention, the 40 blade 10 is rendered adjustable up and down along the face 4 so as to be positioned at just the right position below the top 16 for any particular type of carton.

To this end, the blade, which is preferably of 45 uniform thickness throughout, as shown at 22 in Fig. 4, except along the cutting edge 24, is adapted to be positioned in a diagonally disposed cavity 26 of uniform depth in the top of a clamping member 28, as shown more particularly in Fig. 5. The 50 blade is clamped in position between this clamping member 28 and a further clamping member 30 by screws 32. The clamping member 30 is provided with a diagonally disposed projection 31 corresponding in outline to the outline of the cavity 26 and that of the blade 22, so that the 55 projection 31 bears against the blade 22 equally throughout the limits of the cavity 26, thus to maintain the blade 22 in the cavity 26 with uniform pressure throughout. As a consequence of this construction, the corner 34 alone of the blade 60 projects beyond the cavity 26 and into an opening 36, as shown more particularly in Fig. 2, in the face 4. The opening is of substantial height, as indicated at 38, so that the clamping members 28 and 30, with the blade clamped therebetween, 65 may be adjustably positioned at various levels in the said opening 36.

To substitute one blade 22 for another, it is necessary to remove only one screw 32, and to loosen slightly the other screw 32. The clamping member 30 will then pivot slightly about the loosened screw 32. This provides simplicity in replacement of the blade 22. The blade is so positioned in the cavity 26 that its cutting edge shall face in the direction of travel of the instrument along the box.

Conveniently to provide for the above-described adjustment, the clamp 28 is carried upon a slide 40 that is adjustably mounted in a vertically disposed guide 42 on the outer surface of the face 4, and it may be fixed in adjusted position by means of a screw 44 extending through a slot 46 in the slide 40 and into a screw-threaded opening 48 in the face 4. The screw 44 extends through a boss 62 that is integral with the back of the face 4. This boss provides strength for holding the screw and helps guide the slide 40, which is therefore provided with a recess 64 for this purpose.

The blade 10 and the clamps 28, 30 by which it is carried may be vertically adjusted along the face 4 merely by unscrewing the screw 44, manipulating the slide 40 up and down in the guide 42 until the blade 10 occupies the proper adjusted position on the face 4, and then by retightening the screw 44. To facilitate this operation, the screw 44 may conveniently take the form of a thumb screw, as shown in Fig. 9.

An opening 66 may be provided whereby the instrument may be hung on a hook.

Frequently, a box has a damaged or torn or 10 ripped edge 18; or the edge 18 is provided with a projecting piece 50 through some other cause than damage. In such cases, if the advancing corner 52 of the instrument were to engage this projecting or torn piece 50, further progress 11 would be impeded. According to the present invention, therefore, the inner portions of the forward ends of the faces 2 and 4, at the corner 52 are beveled away, as shown at 54. These beveled faces 54 ride easily over the projecting or torn 12 or ripped pieces, which are then received in the groove 20, thus providing for a clean, even cut 14 all along the side of the box, without interruption of the operation. The forward end of the clamping member 30 is similarly beveled at 60 11 13 all along its forward edge for a similar purpose.

In accordance with the present invention, therefore, the cut 14 may be made in the side wall 12 of the carton at any desired proper distance below the top 16 of the carton, merely by 12 manipulating the instrument in the direction of the arrow in Fig. 1, after grasping the handle 6 with the hand. The groove 20 and the angular relation between the faces 2 and 4 further aids in the proper positioning of the instrument upon 13 the box. The handle 6 is so situated on the upper face 2 of the instrument that not only does it provide a convenient grasping unit, but also it permits exerting the right pressure both downward upon the top face 16 of the carton 14 and inward against the side face 12.

Owing to the construction whereby the handle is of substantial proportions and because of its location, it is impossible for the instrument to slip, and thereby there is removed one source of danger to the operator. More than that, by means of this same, rugged construction, the knife will always be held rigidly and firmly in position on the side of the carton, enabling it to cut cleanly and without causing curling of the paper of the carton, or other defective cut. Because the handle is positioned as it is, and not too far off to one side, it is possible to effect the severing operation by a quick, single movement toward the operator. This single movement results in the severing of the whole, complete side in a single, quick operation.

In accordance with this invention, therefore, boxes of different types may have their tops 16 11

quickly and efficiently removed without any danger of damaging the contents.

It will be understood that the invention is not restricted to the exact embodiment thereof which is illustrated and described herein, but is susceptible of considerable modification and change by persons skilled in the art without departing from the spirit and scope of the invention as defined in the appended claims.

10. What is claimed is:

1. An instrument of the class described for opening a paper box and the like comprising a one-piece member and handle, the member being substantially in the form of a dihedral angle and the handle extending from one of the dihedral faces exterior to the dihedral angle near the line of intersection of the faces thereof, the faces being adapted to be disposed in contact with adjacent faces of the box and the instrument being adapted to be moved along the said adjacent faces by the handle, and a blade extending from the other dihedral face into the corresponding box face.

2. An instrument of the class described for opening a paper box and the like comprising a dihedral angled member the faces of which are adapted to be disposed in contact with adjacent faces of the box, the instrument being adapted to be moved along the said adjacent faces, a blade extending from one of the dihedral faces into the corresponding box face, and means for adjusting the blade toward and from the line of intersection of the dihedral faces.

3. An instrument of the class described for opening a paper box and the like comprising a dihedral angled member the faces of which are adapted to be disposed in contact with adjacent faces of the box, the instrument being adapted to be moved along the said adjacent faces, the instrument having a groove disposed longitudinally along the line of intersection of the dihedral faces for receiving a projecting, rounded edge between the said adjacent faces, and a blade extending from one of the dihedral faces into the corresponding box face.

4. An instrument of the class described for opening a paper box and the like comprising a dihedral angled member the faces of which are adapted to be disposed in contact with adjacent faces of the box, the instrument being adapted to be moved along the said adjacent faces, the instrument having a groove disposed longitudinally along the line of intersection of the dihedral faces for receiving a projecting, rounded edge between the said adjacent faces, the faces of the member being disposed at an angle to each other slightly more than a right angle, and a blade extending from one of the dihedral faces into the corresponding box face.

5. An instrument of the class described for opening a paper box and the like comprising a dihedral angled member the faces of which are adapted to be disposed in contact with adjacent faces of the box, the instrument being adapted to be moved along the said adjacent faces, blade-holding means, and means for disposing the blade holding means at varying positions toward and from the line of intersection of the dihedral faces along one of the dihedral faces so that it may extend into various parts of the corresponding box face.

6. An instrument of the class described for opening a paper box and the like comprising a dihedral angled member the faces of which are adapted to be disposed in contact with adjacent

faces of the box, the instrument being adapted to be moved along the said adjacent faces, one of the faces having an opening and a guide, and a blade-carrying slide disposed near the opening and adapted to be adjusted in the guide toward and from the line of intersection of the dihedral faces.

7. An instrument of the class described for opening a paper box and the like comprising a dihedral angled member the faces of which are adapted to be disposed in contact with adjacent faces of the box, the instrument being adapted to be moved along the said adjacent faces, a clamp comprising two blade clamping members one of which is provided with a diagonally disposed, blade-receiving cavity, means for clamping the blade clamping members together, and means for adjusting the clamp toward and from the intersection of the dihedral faces.

8. An instrument of the class described for opening a paper box and the like comprising a dihedral angled member the faces of which are adapted to be disposed in contact with adjacent faces of the box, the instrument being adapted to be moved along the said adjacent faces, one of the faces having an opening and a guide, a slide disposed near the opening and adapted to be adjusted in the guide toward and from the line of intersection of the dihedral faces, a clamp carried by the slide and comprising two blade clamping members one of which is provided with a diagonally disposed, blade-receiving cavity, and means for clamping the blade clamping members together.

9. An instrument of the class described for opening a paper box and the like comprising a dihedral angled member the faces of which are adapted to be disposed in contact with adjacent faces of the box, the instrument being adapted to be moved along the said adjacent faces, a blade of uniform thickness having an angular cutting edge, a clamp comprising two blade clamping members one of which is provided with a diagonally disposed, blade-receiving cavity of correspondingly uniform thickness and of shape corresponding to the shape of the blade for receiving the blade so that the angular cutting edge may extend from the clamp into the corresponding box face, means for clamping the blade-clamping members together with the blade disposed between them, and means for adjusting the clamp and the blade toward and from the intersection of the dihedral faces.

10. An instrument of the class described for opening a paper box and the like comprising a one-piece member and handle, the member being substantially in the form of a dihedral angle and the handle being disposed exterior to the dihedral angle near the line of intersection of the faces thereof, the faces being adapted to be disposed in contact with adjacent faces of the box and the instrument being adapted to be moved along the said adjacent faces by the handle, the faces being disposed at an angle to each other slightly more than a right angle, the instrument having a groove disposed longitudinally along the line of intersection of the dihedral faces for receiving a projecting, rounded edge between the said adjacent faces, one of the faces having an opening and a guide, a slide disposed near the opening and adapted to be adjusted in the guide toward and from the line of intersection of the dihedral faces comprising two blade clamping members one of which is provided with a diagonally disposed, blade-receiving cavity.

ing cavity, and means for clamping the blade-clamping members together with a blade disposed between them.

11. An instrument of the class described for opening a paper box and the like comprising a dihedral angled member the faces of which are both of substantial width and adapted to be disposed in contact with adjacent faces of the box, the instrument being adapted to be moved along the said adjacent faces, the inner portions of the forward ends of the faces of the member being beveled, and a blade extending from one of the dihedral faces at a substantial distance away from the edges of the faces and into the corresponding box face.

12. An instrument of the class described for opening a paper box and the like comprising a dihedral angled member the faces of which are adapted to be disposed in contact with adjacent faces of the box, the instrument being adapted to be moved along the said adjacent faces, the inner portions of the forward ends of the faces being beveled, one of the faces having an opening, and a clamp comprising two blade clamping members disposed near the opening, the forward end of one of the clamping members being beveled.

13. An instrument of the class described for opening a paper box and the like comprising a dihedral angled member the faces of which are adapted to be disposed in contact with adjacent faces of the box, the instrument being adapted to be moved along the said adjacent faces, one of the faces having an opening, a guide and a threaded boss, a slide disposed near the opening and having a recess for receiving the boss and adapted to be adjusted in the guide toward and from the line of intersection of the dihedral faces, a blade clamped on the slide so as to extend into the corresponding box face, and a screw threaded in the boss for clamping the slide in adjusted position on the guide.

14. An instrument of the class described for opening a paper box and the like comprising a dihedral angled member the faces of which are adapted to be disposed in contact with adjacent faces of the box, the instrument being adapted to be moved along the said adjacent faces, a clamp comprising two blade clamping members one of which is provided with a blade-receiving cavity, and two screws for clamping the blade clamping members together, one of the clamping members being swingable on the other clamping member about one of the screws.

15. An instrument of the class described for opening a paper box and the like comprising a dihedral angled member the faces of which are adapted to be disposed in contact with adjacent faces of the box, the instrument being adapted to be moved along the said adjacent faces, a clamp comprising two blade clamping members, one of the blade clamping members being provided with a diagonally disposed cavity, the other clamping face having a correspondingly diagonally disposed projection, and means for clamping the blade-clamping members together.

16. An instrument of the class described for opening a paper box and the like comprising a one-piece member and handle, the member being substantially in the form of a dihedral angle and the handle being disposed exterior to the dihedral angle near the line of intersection of the faces thereof, the faces being adapted to be disposed in contact with adjacent faces of the box and the instrument being adapted to be moved along the said adjacent faces by the han-

dle, the inner portions of the forward ends of the faces being beveled, the faces being disposed at an angle to each other slightly more than a right angle, the instrument having a groove disposed longitudinally along the line of intersection of the dihedral faces for receiving a projecting, rounded edge between the said adjacent faces, one of the faces having an opening and a guide, a slide disposed near the opening and adapted to be adjusted in the guide toward and from the line of intersection of the dihedral faces comprising two blade clamping members, one of the clamping members being provided with a diagonally disposed cavity, the other clamping face having a correspondingly diagonally disposed projection, and means for clamping the blade-clamping members together.

17. An instrument of the class described for opening a paper box and the like, the said instrument having two faces adapted to be disposed in contact with adjacent faces of the box, the instrument being adapted to be moved along the said adjacent faces and having a longitudinally disposed groove for receiving a projecting, rounded edge between the said adjacent faces, and a blade extending from one of the two faces of the instrument into the corresponding box face.

18. An instrument of the class described for opening a paper box and the like, the said instrument having two faces adapted to be disposed in contact with adjacent faces of the box, the instrument being adapted to be moved along the said adjacent faces and having a longitudinally disposed groove for receiving a projecting, rounded edge between the said adjacent faces, the faces of the instrument being disposed at an angle to each other slightly more than a right angle, and a blade extending from one of the two faces of the instrument into the corresponding box face.

19. An instrument of the class described for opening a paper box and the like, the said instrument having two faces adapted to be disposed in contact with adjacent faces of the box, the instrument being adapted to be moved along the said adjacent faces, the inner portion of the forward end of one of the faces of the instrument being beveled, and a blade extending from one of the two faces of the instrument at a substantial distance away from the edges of the faces of the instrument and into the corresponding box face.

20. An instrument of the class described for opening a paper box and the like, the said instrument having two faces adapted to be disposed in contact with adjacent faces of the box, the instrument being adapted to be moved along the said adjacent faces, the inner portions of the forward ends of the faces of the instrument being beveled, and a blade extending from one of the two faces of the instrument at a substantial distance away from the edges of the faces of the instrument and into the corresponding box face.

21. An instrument of the class described for opening a paper box and the like, the said instrument having two faces adapted to be disposed in contact with adjacent faces of the box, the faces of the instrument being disposed at an angle to each other slightly more than a right angle, the instrument being adapted to be moved along the said adjacent faces, and a blade extending from one of the two faces of the instrument into the corresponding box face.

22. An instrument of the class described for opening a paper box and the like, the said instru-

ment having two walls, both of substantial width, adapted to be disposed in contact with adjacent faces of the box, a handle-carrying projection extending integrally from one of the faces, the instrument being adapted to be moved along the said adjacent faces by the handle, one of the walls having an opening at a substantial distance away from the free edges of the walls, and a blade extending through the opening into the corresponding box face.

23. An instrument of the class described for opening a paper box and the like, the said instrument having two walls, both of substantial width, the inner faces of which are adapted to be disposed in contact with adjacent faces of the box, the instrument being adapted to be moved along the said adjacent faces, the inner portion of one of the faces being beveled, one of the walls having an opening extending therethrough at a substantial distance away from the free edges of the walls, a blade holder disposed near the opening at the outer face of the said one wall, and a blade held by the holder so as to extend through the opening into the corresponding box face in contact with the inner face of the said one wall.

24. An instrument of the class described for opening a paper box and the like, the said instrument having two walls, both of substantial width, the inner faces of which are adapted to be disposed in contact with adjacent faces of the box, the instrument being adapted to be moved along the said adjacent faces, one of the walls having an opening extending therethrough at a substantial distance away from the free edges of the walls, a clamp comprising two blade-clamping members disposed near the opening at the outer

face of the said one wall, a blade adapted to be held between the blade-clamping members so as to extend through the opening and into the corresponding box face in contact with the inner face of the said one wall, and means for clamping the blade-clamping members together with the blade disposed between them.

25. An instrument of the class described for opening a paper box and the like, the said instrument having two faces adapted to be disposed in contact with adjacent faces of the box, the instrument being adapted to be moved along the said adjacent faces, and a blade extending from one of the two faces of the instrument at a substantial distance away from the edges of the faces of the instrument and into the corresponding box face, the blade being adjustable toward and from the line of intersection of the said faces so that it may extend into various parts of the corresponding box face.

26. An instrument of the class described for opening a paper box and the like, the said instrument having two faces adapted to be disposed in contact with adjacent faces of the box, the instrument being adapted to be moved along the said adjacent faces, a blade-carrying slide, and a blade held by the slide so as to extend from one of the two faces of the instrument at a substantial distance away from the edges of the faces of the instrument and into the corresponding box face, the slide being adjustable toward and from the line of intersection of the said faces so that the blade may extend into various parts of the corresponding box face.
